A handwritten signature in cursive script, which appears to be 'Theodor Geisel'.

ATTORNEY

UNITED STATES PATENT OFFICE

169,971

HAT

Theodor Seuss Geisel, La Jolla, Calif., assignor to Columbia Pictures Corporation, New York,
N. Y., a corporation of New York

Application October 8, 1952, Serial No. 21,759

Term of patent 14 years

(Cl. D3—13)

To all whom it may concern:

Be it known that I, Theodor Seuss Geisel, a citizen of the United States of America, residing at city of La Jolla, county of San Diego, and State of California, have invented a new, original, and ornamental Design for a Hat, of which the following is a specification, reference being had to the accompanying drawing, forming a part thereof.

I claim:

The ornamental design for a hat, as shown.

THEODOR SEUSS GEISEL.
